George Van Zandt

UNITED STATES PATENT OFFICE.

GEORGE VAN ZANDT, OF RAVENSWOOD, ILLINOIS.

DATING-BOX FOR SELF-INKING HAND-STAMPS.

SPECIFICATION forming part of Letters Patent No. 289,475, dated December 4, 1883.

Application filed January 30, 1883. (No model.)

To all whom it may concern:

Be it known that I, GEORGE VAN ZANDT, a citizen of the United States, residing at Ravenswood, in the county of Cook and State of Illinois, have invented a new and useful Dating-Box for Self-Inking Hand-Stamps, of which the following is a specification.

My invention relates to a mode of fastening the dating-box to the oscillating die-plate.

10 The objects of my invention are, first, to expedite the changing of dates; second, to level the dates accurately and adjust them to the height of the die; and, third, to permit the dating-line to be used separately (as a "pad stamp") when desired. I attain these objects by the dating-box illustrated in the accompanying drawings, in which—

Figure 1 is a sectional view of an oscillating die-plate with the dating-box in position. 20 Fig. 2 shows the die-plate without the box, and Fig. 3 shows the dating-box alone.

Similar letters refer to similar parts in all the figures.

A indicates the oscillating die-plate of a self-inking hand-stamp.

25 B is a rectangular opening in the plate.

C is a box of thin metal in which the type are to be placed. The ends of the box are open, and the sides may be bent as desired to fit the type.

30 D is a spring, formed as shown, and passing loosely through small sleeves attached to the box C.

E is a notch in each end of the spring. The

notch fits a groove seen on the nut F. F, a 35 grooved nut, adjustable upon screw G; G, a small screw or stud, riveted in the plate A.

The action is as follows: The spring, taken by the thumb and finger, is compressed, and its ends are loosened from the nuts. The box, 40 being lifted out of the rectangular opening, may be used as a pad-stamp independently, (the spring serving as a handle,) or the date in the box may be changed, and when replaced in the die-plate the liberated spring will keep 45 it there. The line is leveled and adjusted by turning the nuts on the screw-thread.

I am aware that previous to my invention a device showing dating-type in an endless band on a metallic shell inclosing a spring by 50 which it is attached to lugs on the die-plate has been patented, and self-inking hand-stamps have been made having dating-type inserted through an opening in the die-plate, and I do not claim any such combination broadly; but 55

What I do claim as my invention, and desire to protect by Letters Patent, is—

The combination, in a self-inking hand-stamp, of the plate A, having the opening B, the screw-studs G, and the grooved nuts F 60 with the type-box C, having small sleeves, and the spring D, passing through the sleeves and engaging with the grooved nuts, all substantially as shown.

GEORGE VAN ZANDT.
